[57] **CLAIM**

The ornamental design for a housing for an automatic telephone alarm system, substantially as shown and described.

DESCRIPTION

FIG. 1 is a front perspective view of a housing for an automatic telephone alarm system, showing our new design;

FIG. 2 is a top plan view thereof;

FIG. 3 is a front elevation thereof;

FIG. 4 is a left side elevation thereof;

FIG. 5 is a rear elevation thereof;

FIG. 6 is a right side elevation thereof;

FIG. 7 is a bottom plan view thereof; and

FIG. 8 is a top front perspective view thereof; the telephone instrument is shown in broken line for illustrative purposes only.
